COMBINED TENT AND SWING FRAME

Filed Dec. 31, 1923

Patented Apr. 24, 1928.

UNITED STATES PATENT OFFICE.

HART E. DELVIN, OF EVANSTON, ILLINOIS.

COMBINED TENT AND SWING FRAME.

Application filed December 31, 1923. Serial No. 683,636.

This invention relates to improvements in combination tent, canopy and swing frames, and one of its objects is to provide a frame that may be used for supporting a tent cover or one or more swings and which, when not in use, may be dismounted for storage in a limited space or for transportation.

Another object of the invention is to provide the frame with notched feet for the accommodation of anchoring pegs or pins to prevent the device from being blown away or tipped over.

These and other aims, objects and purposes which will become later apparent, are attained by the novel construction, combination and arrangement of parts hereafter described in their preferred embodiments and shown in the accompanying drawing, forming a material part of this disclosure, and in which:—

Figure 1 is a perspective view of the invention showing the same covered with tent or canopy material.

Figure 2 is an end view of the device when used to support a canopy over a swing.

Figure 3 is an enlarged fragmentary sectional view taken on line 3—3 of Figure 1 through one of the windows.

Figure 4 is a fragmentary sectional view showing the manner of attaching a carpet or flexible flooring.

Figure 5 is a partial front elevational view of the same.

Figure 6 is an enlarged fragmentary perspective view of the lower end one of the supports.

Figure 7 is a partial plan view taken on line 7—7 of Figure 2 showing a mattress and its supports.

Referring to the drawings in detail, the tent frame consists of a ridge pole 10, preferably made of tubes connected by sleeves and supported at its ends between parallel lugs 12, formed at the upper ends of the converging legs 13 of the end frames, these legs being in sections, jointed as at 14.

As shown, these legs 13 are held in proper position by sectional cross bars 15, connected at their inner ends by pivots 16 and similarly connected at their outer ends to collars 17 fixed to the legs 13. A second set of similar but shorter cross bars 18 are pivoted to like collars 19 and to each other by pivots 20.

Extending inwardly from the collars 19 are other lugs, between which is secured one of the ends of a pair of brace rods 21, their opposite ends being connected to the ridge pole 10.

The legs 13 are flattened at their lower ends and out-turned to provide feet 22, having recesses 23 to receive anchoring pegs or pins (not shown) by means of which the frame is firmly secured to the ground.

The tent cover, generally designated by the numeral 24 is provided with openings 25, bordered on both their outer and inner sides by strips 26 and 27, the inner edges of which overlie respectively, a plate 28 of flexible transparent material, such as celluloid, and a sheet of screen wire 29.

A flap 30 is attached to the cover 24 above each opening and to be rolled up into the position shown in Fig. 1 to admit light into the tent, or extended at length downward to prevent the passage of light as in Figure 3.

In use the frame is set up as shown in the drawing and when used as a tent the cover 24 is fastened at its longitudinal edges with the customary stakes. When it is desired to convert the device into a canopy, sectional poles 31 are passed through the bight of the cover 24 and supported by braces 32 attached at their ends thereto, the other ends of the braces being engaged with the legs 13 causing the cover to assume the position shown in Figure 2 on either or both sides.

It will thus be seen that the cover 24 will provide a canopy and a swing 33, shown in broken lines in Fig. 1, may be suspended from the ridge pole 10.

If desired a floor may be used in conjunction with the frame and cover and is arranged to extend around the bottom ends of the legs 13 and rest on the upper sides of the feet 22 so as to allow for the free circulation of air between its under side and the ground.

A flexible bottom or carpet 35 may also be provided and is attached to the lower edges of the cover 24 by means of buttons 36 which are secured as shown, adjacent the marginal edges of the bottom and pass through aligning button holes formed in the cover and in a flap 38, which is stitched at 39 and 40 to the bottom to provide a longitudinal casing for the reception of the sec-

2
tional rods 31 which is preferably secured in any suitable manner to the legs 13. Openings 42 are provided at intervals in the flap 38 to facilitate the proper jointing of said 5 rods 31.

It is to be understood that the ridge pole 10, legs 13, and braces 20 may be made in solid or in separable sections of nominal length which may be disjointed for storage 10 and transportation and readily fitted and connected together during erection of the frame.

In order to further strengthen the frame when the device is to be used as a sleeping 15 tent, longitudinally extending poles 43, sectional or otherwise, are attached at their ends to the legs 13 by connectors 44, and to these poles are engaged the ends of a plurality of coiled springs 45, their other ends connecting 20 with a strong sheet of textile fabric 46 as duck or canvas, the same acting as a support or mattress for a person in a recumbent position.

The foregoing disclosure is to be regarded 25 as descriptive and illustrative only, and not as restrictive or limitative of the invention, of which obviously an embodiment may be constructed including many modifications without departing from the general scope 30 herein indicated and denoted in the appended claims.

Having thus described my invention, what I claim as new and desire to secure by Letters Patent, is:—

35 1. A tent comprising a ridge-pole having

a pair of divergent legs at each end, said legs being composed of cylindrical tubular sections pivoted at their points of intersection, foldable braces independently connecting the upper and lower sections of each pair of 40 legs, arms pivoted to the upper section of one of each pair of legs, said arms being angularly extensible or closely foldable alongside the legs, a pole extending between the lower ends of said legs on each side, 45 said pole being also engageable with the outer ends of said arms when said arms are folded, a cover extensible over said ridge-pole between said pairs of legs to the lower ends thereof, means to secure said cover to 50 said pole, and means to secure the edges of said cover to the main portion thereof when the pole is elevated by said arms to constitute a canopy.

2. In a tent support, a frame composed of 55 a ridge element, divergent legs pivoted to each end of said ridge element, longitudinal rails connecting said legs at the bottoms thereof, braces pivoted to fold flat between each pair of legs, and tensional elements connecting said rails.

3. In a tent support, a collapsible frame composed of a rigid ridge element, pairs of 60 jointed sectional legs pivoted to the ends of said ridge element, foldable braces extending between the legs constituting each pair, and a canopy adjustable on said support.

In testimony whereof I have signed my name to this application.

HART E. DELVIN.
